UNITED STATES PATENT OFFICE

JOHAN FRANCOIS BARTHOLD VAN HASSELT, OF AMERSFOORT, NETHERLANDS, AS-SIGNOR, BY DIRECT AND MESNE ASSIGNMENTS, TO CHEMISCHE INDUSTRIE VAN HASSELT, OF AMERSFOORT, NETHERLANDS, A DUTCH COMPANY, AND ADRIANUS KLEIJN, OF ROTTERDAM, NETHERLANDS

TREATMENT OF MEAL, FLOUR OR MILLING PRODUCTS

No Drawing. Application filed February 28, 1929, Serial No. 343,565, and in the Netherlands March 20, 1928.

It is known that nitrogen oxides and derivatives thereof such as nitrosylchloride, are excellent means for bleaching flour and improving its baking qualities.

5 The handling of these dangerous gaseous substances, which intensely affect the mucous membrane, has various other drawbacks, among which is a deleterious action on the material of the cylinders, valves, conduits etc. of the mechanism employed. The proper measurement of said gases is also a somewhat difficult matter.

10 On the other hand these gaseous bleaching agents have the great advantage over bleachers which are applied in a state of fine subdivision to the flour, especially benzoyl-peroxide, which is suitable for use and can easily be measured, that they act practically instantaneously; the bleaching process being accomplished in a few seconds after the bleaching substance has been mixed with the flour.

15 The object of the present invention is to combine the advantages of bleaching by means of solid substances with the advantages of bleaching by means of nitrogen-oxygen compounds by introducing the latter in an easily measurable and handy form, i. e. as finely pulverized solid substances or 20 solutions. In this way the bleaching agent can be easily transported and accurately measured. The finely pulverized solid substances or the solutions may contain the bleaching agent adsorbed, dissolved, chemically bound or simply mixed therewith, but the substances must always be such that when mixed with the flour the desired bleaching nitrogen compounds develop very quickly.

25 40 According to the invention I employ a non-gaseous composition containing at least one substance belonging to a nitrosyl group from which a bleaching nitrogen compound is formed as soon as said composition is 45 mixed with flour of ordinary moisture content. The composition may be used for bleaching various kinds of meal and flour and milling products generally, including potato flour.

50 The substance belonging to a nitrosyl

group from which a bleaching nitrogen compound is formed when mixed with flour of ordinary moisture content, may be a mixed anhydride of nitrous acid and another acid, preferably a non-oxidizing acid. A suitable 55 substance is N_2O_4 , which may be regarded as a mixed anhydride of nitrous acid and nitric acid.

This substance may be used dissolved in a suitable solvent. Another suitable substance is nitrosylchloride, which is a mixed anhydride of nitrous acid and hydrochloric acid. This substance may be used in the form of a double compound with metallic chlorides such as ferric chloride, stannic 60 chloride, titanic chloride and the like from which, in the presence of moisture, the gas $NOCl$ is liberated exceedingly rapidly and further decomposes or is capable of decomposition into N_2O_3 and $HC1$. 70

75 Other suitable substances are nitrosyl acetic acid, nitrosyl benzoic acid, nitrosyl selenic acid, the compound $SO_3N_2O_3$ (melting point 200° C., see Pictet, Chem. Centralblatt 1909, vol. 1, page 340) and especially nitrosyl sulfuric acid.

80 As stated above, according to the invention all these substances are used in combination with solid or liquid substances, in which they are adsorbed, dissolved, chemically bound or simply mixed in such manner that the whole composition can easily be handled and does not develop the dangerous gaseous nitrosyl compounds before admixture with the flour or meal. It is however evident that the treating compositions should be stored and kept in such manner that contact with moisture is excluded. 85

90 As already remarked a very suitable substance is nitrosyl sulfuric acid. This easily-decomposable, very hygroscopic substance may be stabilized for use by mixing with well-dried, preferably-active, silicic acid, such as fuller's earth, and most suitably with silica gel. This mixture is used in the 95 form of a fine dry powder.

95 The rapid and complete decomposition of the compositions according to the invention in flour and the accomplishment of bleaching in a few seconds are most surprising. 100

As solutions there may be mentioned those of N_2O_4 in any suitable solvent, as for example glacial acetic acid, benzene or the like, also solutions of nitrosylchloride in benzene, toluene or glacial acetic acid etc. The solid and liquid compounds may also be combined by applying, for instance, solutions of the abovementioned double compounds of nitrosylchloride with ferric chloride, stannic chloride, titanic chloride or the like. Chlorine and/or bromine may also be dissolved therein, whereby compounds such as $NOCl_2$ may be formed, thus uniting the advantages of the chlorine treatment (Kent Jones, Modern Cereal Chemistry, page 17, 21) and bleaching.

As already observed, the active agent in the composition according to the invention is a substance belonging to the nitrosyl group, from which a gaseous bleaching nitrogen compound is formed when the composition is mixed with flour of ordinary moisture content. Though the moisture content present in ordinary flour is more than sufficient to decompose the active substances in the composition at ordinary temperature, and the gaseous nitrosyl compounds formed thereby have a bleaching action and improve the baking qualities of flour, it may be that in some cases an actual decomposition does not occur, but that the active substance acts with its entire molecule directly on the colouring matter in the flour. It has been observed that the action of nitrosyl sulfuric acid, in the form in which it is used according to the invention, is quicker and better than the action of an equivalent quantity of gaseous nitrogen oxides.

As the substances according to the invention act very quickly at ordinary temperature, it is sufficient to mix them well with the flour or meal and no after-treatment is necessary, though of course if desired, any after-treatment may be used and is within the scope of the present invention.

Example 1

1 part of a mixture of 1 part of nitrosyl sulphuric acid and 1 part of active silicic acid is mixed in an agitator with 20.000 parts of flour. The flour instantly attains a fresh yellow colour.

Example 2

55 1 part of the double compound of ferric-chloride and nitrosylchloride is mixed in the same manner with 25.000 parts of flour. The bleaching is perceptible instantaneously.

What I claim is:

60 1. A process for treating meal, flour and milling products which normally contain moisture which comprises adding thereto a small quantity of an intimate mixture of nitrosyl sulphuric acid and a solid substance, 65 the nitrosyl sulphuric acid of which reacts

with the moisture of the meal, flour and milling products to yield a gaseous nitrogen bleaching compound.

2. A process for treating meal, flour and milling products which normally contain 70 moisture which comprises adding thereto, in combination with a solvent, a small quantity of a substance selected from the group consisting of nitrosyl chloride-ferric chloride, nitrosyl chloride-stannic chloride, nitrosyl chloride-titanic chloride, nitrosyl acetic acid, nitrosyl benzoic acid, nitrosyl selenic acid, and the compound represented by the formula $SO_3N_2O_3$; which substances react with the moisture normally contained in the meal, flour and milling products to yield a gaseous nitrogen bleaching compound. 75

3. A process for treating meal, flour and milling products which normally contain 80 moisture which comprises adding thereto solid material comprising a small quantity of a substance selected from the group consisting of nitrosyl chloride-ferric chloride, nitrosyl chloride-stannic chloride, nitrosyl chloride-titanic chloride, nitrosyl acetic acid, nitrosyl benzoic acid, nitrosyl selenic acid, and the compound represented by the formula $SO_3N_2O_3$; which substances react with the moisture normally contained in the meal, 85 flour and milling products to yield a gaseous nitrogen bleaching compound. 90

In testimony whereof I affix my signature.
JOHAN FRANÇOIS BARTHOLD van HASSELT.
